UNITED STATES PATENT OFFICE.

JOHN EVANS, OF MELVILLE STATION, NEWPORT COUNTY, RHODE ISLAND.

CHECK PROTECTOR.

Application filed July 9, 1925. Serial No. 42,574.

To all whom it may concern:

Be it known that I, JOHN EVANS, a citizen of the United States, and a resident of Melville Station, in the county of Newport 5 and State of Rhode Island, have made certain new and useful Improvements in Check Protectors, of which the following is a specification.

My present invention relates generally to 10 check protectors of the type described and claimed in my Patent 1,182,001, granted May 9, 1916, and with respect to which my present invention proposes certain improvements permitting of more ready application 15 and effective use of the implement without impairing its adaptability to ready transportation in the pocket or any other small storage spaces.

A further object of my present invention 20 is to provide a small neat compact device in which the impression members are carried by the side portions of a frame permitting of movement of the impression members toward and away from one another, means 25 being included for normally holding the impression members in spaced apart relation and other means being employed for forcing the same toward and into engagement with one another with ample pressure 30 brought about by mere hand manipulation, to cause the serrated opposing faces of the impression members to indent that portion of a check disposed between the impression members.

A still further object is the provision of 35 a device of the above character in which the impression members are elongated and so connected to the adjacent portions of the frame that their direction of greatest length 40 may be positioned either parallel with or transversely of the frame, in order that the device may be utilized with equal convenience and effectiveness upon check forms of different characters.

In the accompanying drawing which illustrates my present invention and forms 45 part of this specification:

Figure 1 is a perspective view illustrating the practical application of my invention;

Figure 2 is a similar view showing my invention in a different position from that 50 illustrated in Fig. 1;

Figure 3 is a vertical longitudinal section 55 taken centrally through my improved protector;

Figure 4 is a side elevation thereof showing the same in closed position, and,

Figure 5 is a perspective view showing certain parts in detailed and spaced relation.

Referring now to these figures, my invention proposes a check protector including a U-shaped frame 10, which may be formed in two sections connected by a hinge 11 as 60 illustrated in Figs. 1 to 3, inclusive, or which may be formed of a single piece of metal, as shown in Fig. 44, having sufficient elasticity to permit of flexure of the free ends of the frame toward and away from one another.

The free ends of the frame have their inner faces provided with circular recesses 12, and these free ends of the frame have apertures 13 centrally of these recesses, and are 65 provided with pins 14 upstanding in the recesses for a purpose which will be presently made plain.

The two impression members 15 and 16 70 have interfitting serrated opposing faces 17 and are provided centrally of their length 80 with outstanding circular bosses 18, the latter adapted to movably interfit the recesses 12 of the frame sides. These bosses are provided with arcuate slots 19 to receive pins 14 and also have central threaded openings 85 for the reception of the inner portions of screws 20, the latter passing through the apertures 13 of the frame sides in order to movably hold the impression members in 90 such manner that they may be turned lengthwise of the frame, as in Fig. 2, or at right angles to the frame as at Fig. 1, the pins 14 working in the slots 19 and the ends of the slots thus constituting the limits of shifting movement of the impression members 15 and 16. The impression members are of 95 narrow elongated form and thus when turned lengthwise of the frame as in Fig. 2, are adapted to receive one end of a check form between the same, whereby the impression 100 may be conveniently made across the numerical amount of the check where the space for such amount is formed near one end of the check. On the other hand, by turning the impression members through 90 degrees to the position shown in Fig. 1, the impression members are adapted for the reception of one side edge portion of the check therebetween in order that the impression may be 105 conveniently made along the numerical 110

amount of the check where the same is placed as it is in some instances adjacent to the lower left hand corner of the check.

It will be noted from Fig. 5 in particular 5 that the aperture 13 of one of the frame sides has upon the outer side of the frame a surrounding boss 21, a portion of which is cut away so as to expose a portion of the respective supporting screw 20 below its 10 head.

One of the frame sides has a stud 22 securely fastened in connection therewith and projecting through a substantially larger opening 23 on the other frame side, this stud 15 being located remote from the free ends of the frame to a sufficient extent to prevent interference with the swinging adjustment of the impression members. To the free end of the stud 22 is pivoted one end of a lever 24 having adjacent to its said pivoted end a cam shoulder 25 and having adjacent to its free end a sliding latch stud 26, the latter of which is provided at its lower end below the lever with an engaging lip 27 for extension 20 beneath the head of the adjacent supporting screw 20 when the lever 24 is pressed downwardly to the position shown in Fig. 4 and the latch stud forced forwardly into the cut 25 out portion of the upper boss 21.

With the device in the position shown in 30 Fig. 4, it is simply necessary to place the thumb on the free end of the lever 24 over the latch stud 26, in order that slight pressure on the lever and rearward sliding movement may free the latch stud, and incidentally free the lever. Upon release of pressure, a spring 28 around the stud 22 and compressed between the two sides of the frame, tends to force the frame sides away 35 from one another and thus tends to separate the impression members to the position shown in Fig. 3. The impression members are then extended over the end of a check as in Fig. 2, or over the side thereof as in Fig. 45 1, after adjustment to a position at right angles to the frame, and by means of the thumb on the lever 24, the impression members are then forced toward one another so as to indent those portions of the check 50 therebetween by pressing downwardly upon the free end of the lever 24, the cam shoulder 25 of the latter engaging the adjacent side of the frame.

The device as thus described may be small 55 and compact, is strong and durable, is powerful in its action; and is obviously capable of effective and efficient use.

I claim:—

1. A check protector including a pair of 60 elongated impression members having serrated opposing faces and having their opposite ends provided with outstanding bosses centrally between the ends thereof, a U-shaped supporting frame having the ends 65 of its extensions provided at their inner

sides with recesses to receive said bosses, threaded fasteners projecting through the extensions of the frame and engaging the bossed portions of the impression members to hold the same rotatably in position whereby they may be shifted from longitudinal to a transverse position with respect to the frame, and hand actuated means for shifting the extensions of the frame toward one another. 75

2. A check protector including a pair of elongated impression members having serrated opposing faces and having their opposite ends provided with outstanding bosses centrally between the ends thereof, a U-shaped supporting frame having the ends 80 of its extensions provided at their inner sides with recesses to receive said bosses, threaded fasteners projecting through the extensions of the frame and engaging the bossed portions of the impression members to hold the same rotatably in position whereby they may be shifted from longitudinal to a transverse position with respect to the frame, and hand actuated means for shifting the extensions of the frame toward one another including a stud projecting from one extension of the frame through the other extension thereof, and a cam lever pivoted 85 on the said stud and engageable with the last mentioned extension of the frame. 90

3. A check protector including a pair of impression members having opposing serrated faces, a U-shaped frame in the ends 100 of the extensions of which the said impression members are rotatably mounted for movement from a longitudinal to a transverse position with respect to the frame and vice versa, said frame and said impression members having relatively engaging means 105 to limit adjusting movement of the impression members and clamping means in connection with the frame for shifting the extensions thereof toward and away from one another. 110

4. A check protector including a pair of impression members having opposed serrated faces, a U-shaped frame at the ends 115 of the extensions of which said impression members are mounted, one of the extensions of said frame having a stud projecting from one of the extensions of the frame and through the other extension thereof, a lever pivoted at one end to the free end of the stud and having adjacent to its pivot a cam for engagement at the other frame extension, said frame and free end of said lever having relatively engaging means to secure the lever against the frame. 120

5. A check protector including a pair of impression members having opposed serrated faces, a U-shaped frame at the ends 125 of the extensions of which said impression members are mounted, one of the extensions of said frame having a stud projecting from 130

one of the extensions of the frame and through the other extension thereof, a lever pivoted at one end to the free end of the stud and having adjacent to its pivot a cam 5 for engagement at the other frame extension, said frame and free end of said lever having relatively engaging means to secure the lever against the frame, including a finger actuated latch member slidably 10 mounted in connection with the lever, as described.

6. A check protector including a U-shaped

frame whose extensions are movable toward and away from one another, a pair of impression members of elongated shape, having serrated opposing faces and movably mounted in connection with said frame extensions for adjustment from a lengthwise 15 to a transverse position and vice versa, and clamping means in connection with the 20 frame for moving its extensions and the said impression members toward and away from one another.

JOHN EVANS.
